UNITED STATES PATENT OFFICE.

WILLIAM A. PERVIER, OF WATERTOWN, MASSACHUSETTS, ASSIGNOR TO CHARLES E. PARKHURST, OF SOMERVILLE, MASSACHUSETTS.

SIPHON PUMP.

Application filed February 27, 1924. Serial No. 695,464.

To all whom it may concern:

Be it known that I, WILLIAM A. PERVIER, a citizen of the United States of America, and resident of Watertown, in the county 5 of Middlesex and State of Massachusetts, have invented new and useful Improvements in Siphon Pumps, of which the following is a specification.

This invention relates particularly to a 10 device adapted to be carried in automobiles to transfer gasoline from one tank to another, and it has for its object to provide a device which can be inserted into a deep tank through a small opening, which is adapted 15 to siphon a liquid from one tank to another after flow is established, which is simple and inexpensive in construction, yet effective and durable in use, which cannot be disarranged by tampering and which will withstand 20 rough usage such as that to which tools are ordinarily subjected when carried loosely in the tool box of an automobile.

For the purpose of illustration one concrete embodiment is shown in the accompanying drawings, in which:—

Fig. 1 is a side elevation;

Fig. 2 is a central longitudinal section; and

Fig. 3 is an enlarged view of the tip end.

The particular embodiment of the invention chosen for the purpose of illustration comprises a barrel A preferably formed from a piece of tubing, a plunger B telescoping over the upper end of the barrel, a head C telescoping over the lower end of the barrel, an outlet tube D extending upwardly along one side of the barrel, and a flexible tube E extending from the upper end of the outlet tube D to a point below the lower end of the barrel. The head C is preferably sweat-ed upon the barrel A so that the two parts are integrally connected together. The lower end of the head C is provided with two cross-cuts F so that the inlet G is not ob- 45 structed when the head rests on the bottom of a tank. A ball valve H seats downwardly in the head C to act as a check valve. The tube D is connected to the head C through the medium of a right angle coupling I which is threaded through the head C and thence into the barrel A thereby further locking the head to the barrel and serving as a stop to limit the upward movement of the ball valve. The tube D is preferably 50 sweat-ed into the coupling I and the space 55

between the coupling and the head C is preferably filled with solder as indicated at K in Fig. 2, whereby the parts are integrally connected together. The barrel A and tube D are interconnected just below the normal 60 position of the plunger B by means of an endless clip L, which fits around both parts, the sides of the clip being pinched together or almost together between the tube and barrel and the clip being brazed to both the 65 tube and the barrel. A ring M is fixedly attached to the tube D within the loop N by means of an endless clip O which surrounds the ring and tube and is brazed to both parts.

The plunger B is formed of tubing some-what larger than the barrel and a ring P is brazed in the lower end thereof to form a guide for the plunger and also to serve as a stop adapted to limit the upward move- 70 ment of the plunger by engagement with the packing ring Q which is brazed to the barrel A near the upper end. A second packing ring Q' is brazed to the upper end of the barrel and the space between the two pack- 75 ing rings is filled with packing material R. A cap S is brazed over the upper end of the tube of the plunger B tightly to close the 80 upper end.

In assembling the parts the rings Q and Q' are brazed upon the barrel and the ring P is brazed to the plunger. The plunger is telescoped over the lower end of the barrel A and the cap S is later brazed over the upper end of the plunger, the packing 85 material R being applied before the cap S is applied to the plunger. The clip L is then fitted over the barrel and outlet tube; the head C is then brazed over the lower end of the barrel; the coupling I is then thread- 90 ed into the head and barrel; the tube D is then brazed in the coupling I; after which the clip L is brazed to the tube and barrel and the solder K applied. After the 95 parts are assembled the entire device is pref- 100 erably nickled.

In operation the lower end of the device is inserted into a gasoline tank or other tank from which liquid is to be withdrawn and the plunger S is reciprocated until the tubes 105 D and E are filled and flow is established. If the receptacle into which the liquid is discharged is lower than the tank from which the liquid is withdrawn the flow con- 110 tinues siphonical; otherwise the flow may

be maintained by continued reciprocation of the plunger P.

Owing to the fact that the connection between the barrel and outlet tube is at the lower end of the barrel, liquid will rise into the barrel and outlet tube above the interconnection therebetween, whereby the outlet is sealed by the liquid and no check valve is required in the outlet. The long narrow outlet pipe extending upwardly along the barrel and thence downwardly also helps to make it possible to eliminate the check valve in the outlet.

From the foregoing it will be evident that this device is fool-proof, durable and highly useful as an automobile accessory for emergency use when a gasoline tank unexpectedly runs dry.

I claim:

1. A device of the character described comprising a barrel having a hollow handle telescoped over its upper end and a hollow head telescoped over its lower end, said handle having a tight sliding fit with the barrel and said head being fast thereto, and a ball valve seating downwardly in said head, said head having a cross-cut in its lower end to admit liquid when resting upon the bottom of a container.

2. A device of the character described comprising a barrel having an inlet at its lower end, a ball valve seating downwardly above said inlet, and an outlet connection to the barrel near its lower end, the end of said connection extending into the barrel to serve as a stop for said ball valve.

3. A device of the character described comprising a barrel, a plunger, telescoping therewith, a hollow head telescoped over the lower end of the barrel and fast thereto, a ball valve seating downwardly in said head, and an outlet tube extending through said head and into said barrel, thereby locking the head to the barrel, said tube also serving as a stop to limit the upward movement of the ball valve.

4. A device of the character described comprising a barrel, a plunger telescoping therewith, a hollow head telescoped over the lower end of the barrel and fast thereto, a ball valve seating downwardly in said head, and an outlet tube extending through said head and into said barrel, thereby locking the head to the barrel.

Signed by me at Boston, Massachusetts, this twenty-fifth day of February, 1924.

WILLIAM A. PERVIER.
